UNITED STATES PATENT OFFICE.

ELLSWORTH FORD, OF WESTVILLE, CONNECTICUT.

METALLIC BARREL-HOOP.

SPECIFICATION forming part of Letters Patent No. 298,962, dated May 20, 1884.

Application filed October 16, 1883. (No model.)

To all whom it may concern:

Be it known that I, ELLSWORTH FORD, of Westville, in the county of New Haven and State of Connecticut, have invented certain 5 new and useful Improvements in Metallic Barrel-Hoops, of which the following is a full, clear, and exact description.

Reference is to be had to the accompanying drawings, forming part of this specification, in 10 which similar letters of reference indicate corresponding parts in all the figures.

Figure 1 is a perspective view of one of my improved barrel-hoops. Fig. 2 is a side elevation of a part of the same, showing its ends 15 twisted through one-quarter of a revolution and overlapped, ready to be coiled. Fig. 3 is a cross-section of the same, taken through the line *x x*, Fig. 2, and showing a part of a stave in section. Fig. 4 is a perspective view of a 20 piece of hoop-iron. Fig. 5 is a cross-section of the overlapped ends, taken through the line *y y*, Fig. 2. Fig. 6 is a perspective view of a piece of hoop-iron, showing a modification. Fig. 7 is a perspective view of a piece of hoop-iron, showing another modification. 25

The object of this invention is to provide metallic hoops for barrels and other casks and vessels made of staves, and which shall be cheaper, stronger, and more durable than the 30 ordinary wooden hoops. Upon the inner or flat side of the hoop is formed a rib, which may be continuous or in sections, and which, when the hoop has been driven into place, will bed itself in the wood, and thus hold the 35 hoop in place upon the cask, as will be hereinafter fully described.

The hoop A is made of half-round iron of such a size as the character of the cask or vessel to which it is to be applied may require.

The ends of the iron of which a hoop is to be 40 formed are twisted through a quarter of a revolution in opposite directions to bring the flat sides of the said ends toward each other, and are slightly inclined—one upward and the other downward—to keep the body of the hoop 45 in line. Each end of the hoop-iron is then coiled around the body of the hoop adjacent to the other end, as shown in Fig. 1, so as to connect the two ends firmly together, and in such a manner that they will not draw apart or 50 slip upon each other when the hoop is driven upon the cask. The inner or flat side of the hoop A has a rib, B, formed upon it, which rib B may be in the middle part of the said flat side, as shown in Figs. 1, 3, 4, and 5, or 55 along one edge of the said side, as shown in Fig. 6. The rib B may be continuous, as shown in Figs. 4 and 6, or in sections, as shown in Fig. 7. With this construction, when the hoop A has been driven into place upon the 60 cask, the rib B will soon bed itself in the wood, as illustrated in Fig. 3, so that the said hoop will be held securely in place without being nailed or otherwise fastened.

I am aware that wire has been crimped or 65 corrugated and cut in lengths to form hoops; also, that studs or ribs are not new on the under side of hoops; but

What I claim as new is—

A new article of manufacture consisting of 70 a half-round metal hoop-blank twisted at its opposite ends in reverse directions for a quarter-revolution, thus bringing toward each other the flat sides of the ends, as described.

ELLSWORTH FORD.
